UNITED STATES PATENT OFFICE.

WILLIAM D. MOUNT, OF SALTVILLE, VIRGINIA, ASSIGNOR TO NITROGEN PRODUCTS COMPANY, OF PROVIDENCE, RHODE ISLAND, A CORPORATION OF RHODE ISLAND.

CYANID-PRODUCING APPARATUS.

1,329,721.

Specification of Letters Patent.

Patented Feb. 3, 1920.

Application filed April 26, 1918. Serial No. 230,876.

To all whom it may concern:

Be it known that I, WILLIAM D. MOUNT, a citizen of the United States, residing at Saltville, in the county of Smyth and State 5 of Virginia, have invented certain new and useful Improvements in Cyanid-Producing Apparatus, of which the following is a specification.

This invention relates to apparatus for 10 affecting chemical reactions and more especially to a furnace in which solid or semi-solid reaction materials are caused to feed through a preferably continuously operating retort, while free nitrogen is caused to react 15 upon said materials to fix said nitrogen.

One of the objects of said invention is to 20 provide means for inducing a regulated flow of reaction material through a retort or the like to the end that proper reaction conditions may be maintained in said retort. Another object is to provide a combination 25 of parts through the intermediacy of which the treated material is very efficiently cooled and is preserved from contamination by air until its temperature is so much lowered that 30 such contamination cannot occur when through inadvertence, or otherwise, air gains access to the treated mass.

These and other objects of my invention 35 will be hereinafter referred to and the novel combinations of means and elements whereby said objects may be attained will be more particularly pointed out in the appended claims.

In one of its aspects my invention concerns an improvement upon the apparatus shown in the patent to John E. Bucher, No. 1,120,682, dated December 15, 1914, in which a furnace is shown through a retort in 40 which a column of briquetted material is fed by gravity while a current of nitrogen or nitrogenous gas is caused to ascend the column, successively cooling the briquets which have traversed the reaction zone, the 45 nitrogen being preheated in so doing,—and then passing through or into the highly heated portion of the retort to react with carbonaceous material and sodium carbonate or the like in the charge, to form, for example, sodium cyanid.

In operating furnaces of this description, however, considerable difficulty has been en-

countered in removing the cyanized material from the retort, owing to the binding property of the cyanid formed.

The charge while passing through the heat zone of the apparatus acquires a high content of cyanid, and when the cyanized mass passes into the cooling zone below, the cyanid hardens, with the result that the 55 charge, initially supplied in pieces or preferably in the form of briquets, is united into a fairly solid column; the cyanid acting as a binder to unite the briquets wherever they make contact with each other.

This column is, of course, filled with interstices when the operation is properly conducted; and the passage of nitrogen up 60 therethrough is hence not materially hindered.

It is sufficiently rigid and strong, however, to offer a problem as how best to disintegrate it without too severely jarring the retort, since heavy continuous vibration obviously tends to shorten the life of the apparatus.

It is also desirable not to unnecessarily pulverize the cyanized material on account 70 of objection to such powder during subsequent operations. The apparatus shown in the drawings fulfills these requirements and 75 will now be considered in some detail.

In said drawings which form parts hereof and in which like reference characters designate like parts in the respective views, I have shown a preferred embodiment of my invention; but as I am aware of various changes and modifications which may be made herein without departing from the spirit of said invention, I desire to be limited only by the scope of the claims, broadly interpreted in 80 the light of my disclosure.

Referring to the drawings:

Figure 1 is a side elevation of my improved cyanizing apparatus; said elevation being partly broken away to show details of 85 construction.

Fig. 2 is a rear view of the lower part of 90 said apparatus; the view being taken from the line II—II of Fig. 1.

Fig. 3 is a detail section taken on the line 100 III—III of Fig. 1; and,

Fig. 4 is a detail section taken on the line 110 IV—IV of Fig. 1.

The apparatus preferably comprises a

retort 1, of iron or other suitable material, which projects up through the furnace brick-work 2, and similarly extends down through the bottom plate 3; the preferably 5 enlarged lower end 1' of said retort being seated in the mouth of the feed-table casing 4.

A gas-tight seal at the lower end of the retort is formed by compressing a packing 10 of kieselguhr or other suitable material 5 around the outer wall of said retort, by means of an annular casting 6.

The preferably continuously moving charge 7, is fed into the hopper 8, and portion after portion thereof drops gradually and successively down through the pre-heating section of the retort until it enters the reaction zone within the heated chamber 9; after which it is cooled somewhat in 20 the enlarged section 1', before entering the casing 4.

The chemistry of the reaction need not be here further considered other than to state that in the preferred methods of conducting 25 the operation, the charge is composed of briquets, the ingredients of which may be, for example, sodium carbonate, pulverized coke, charcoal, or the like and finely divided iron. Nitrogen is supplied to this charge in 30 the manner hereinafter described, so that at a temperature of, say, 1000° C., the carbon of the coke or charcoal is caused to unite with the free nitrogen and with sodium supplied by the sodium carbonate, to form cyanide. This reaction is preferably effected 35 catalytically through the intermediacy of the iron, and by the time that a given briquet arrives at the bottom of the heat zone, it is normally highly cyanized.

40 During their progress through the heat zone, the cyanide present in the briquets is normally molten, in large part, but as the cyanized material enters the cooling section 1', its fluid content commences to congeal; with the result that by the time such material enters the casing 4, it has set into a quite rigid column.

A rotary table 10 in this casing supports 45 said column, and is provided with means for breaking off briquets or fragments thereof from the bottom of the column to enable the charge in the retort to gradually descend.

The preferred device for this purpose, is a star 11, having three points or arms and provided 55 with pyramidal teeth 11' to pick or pry off the briquets without materially pulverizing them. Said star is loosely pivoted upon the upper surface of table 10, with its axis of rotation 12 eccentric to that of the 60 table, as shown in Fig. 3, wherein the location of the shaft 13 which supports said table is indicated by a dotted circle.

Shaft 13 is suitably journaled in bushings 13-15' disposed respectively in the base 65 member or plate 14 and its yoke 16; the

table shaft being driven by a worm wheel 17, which in turn is driven by a worm 18 mounted on a shaft 19 which is preferably caused to revolve step by step by means of a ratchet wheel 20 and pawl 21. Wheel 20 70 is of course secured to the shaft 19 and the pawl 21 is carried on an arm 22, pivoted on shaft 19, in a known fashion.

The shaft 19 is journaled in the yoke 16 and in a bearing 23 attached to one side of 75 the hopper 24, which may conveniently be made a part of the base plate 14.

The hopper 24 receives the separated briquets or fragments thereof, thus preferably pried off from the charge, and delivers them to a cooling tank 25. This tank is preferably, what may be termed, "flat", being quite narrow in proportion to its breadth and depth, as shown in Figs. 1 and 2; so that it affords a very extensive surface, in proportion to its volume or cubical content, to permit of air or water cooling 85 and cooling by radiation.

It may be here noted that the material to be cooled is a relatively poor conductor 90 of heat; but by thus providing a large "flat" tank, the distance from the most interiorly disposed point in the mass to be cooled, to the exposed cooling surface need not be over two or three inches. The tank 95 is also preferably tapered toward the bottom, as shown, to still further reduce said distance, with the result, that the temperature of the material drawn from valve 26 at the lower end of said tank is normally but 100 very little above that of the surrounding atmosphere.

In the construction given by way of illustration, a bearing bracket 27 is mounted upon one side of the tank, and has journaled therein a shaft 28, one end of which carries an eccentric 29, and the other end a sprocket wheel 30 or the like. A rod 31 connects the eccentric strap 29' with the arm 22, so that as the shaft 28 is rotated by 105 the wheel 30, rod 31 oscillates the arm 22, to cause the pawl 21 to step the ratchet wheel around whereby to cause a corresponding step by step but much slower rotary motion of the feed table.

As this action takes place, on account of the eccentricity of the star 11 with respect to said table, the teeth 11' are caused to powerfully pry or pick fragments from the column above the table; first one tooth coming into play and then another, or, at times, possibly two of the teeth, simultaneously breaking off fragments.

A further advantage in thus eccentrically mounting a loosely pivoted toothed element 125 upon the rotary table, is that the charge is prevented from idly rotating in its retort; as it is apt to do where the table itself carries the teeth and has its axis co-incident with that of a cylindrical retort.

The tank preferably has a capacity two or three times that of the retort, when air cooled as shown.

Air is excluded from the tank and of course from the casing 4 and retort, to prevent the oxidation of the cyanid formed, to cyanate; and for this and other reasons hereinafter noted, nitrogen is introduced into the bottom of the tank through a pipe 32; 10 the flow of gas being controlled by means of valve 33.

The nitrogen current flows up through the tank, between the interstices of the briquets or charge fragments, aiding in cooling said 15 fragments and in turn being preheated by contact with them.

By the time that it enters the casing 4 and passes thence through the laterally unsupported walls of the rigid briquet column, 20 into retort section 1', it is quite hot; but still of course below the melting point of cyanid. As it thereafter traverses the pores and interstices of the briquetted charge, it is gradually raised to the reaction temperature, while again in turn aiding in cooling 25 the descending cyanized charge, to cause any liquid present in the latter to congeal or solidify.

The valve 26 at the lower end of the cooling receptacle, is preferably a one-way 30 valve, as shown in Fig. 4; having therein a pocket 26' so that when it is, for example, continuously rotated, this pocket is alternately filled and emptied at every revolution.

Preferably this valve is driven slowly by means of a sprocket and chain drive; shaft 19 having feathered on one end a clutch 34 which when operatively disposed causes said 40 shaft to drive a sprocket wheel 35, which in turn actuates a chain 36 to drive a sprocket wheel 37 mounted on a trunnion 38 of said valve 26. Normally, of course, before the clutch is thrown to cause valve 26 to rotate, 45 a receiving can 39 is placed in position below the valve casing 40.

The general operation of the apparatus may now be briefly reviewed.

Assuming that the retort is charged with 50 briquets and that its heat-zone section has attained the proper temperature, the supply of heat being maintained by the flow of hot gases through the furnace in the direction of the arrows; the charge will then gradually move down through the retort, each briquet being first pre-heated by the ascending gaseous reaction products.

Thereafter each briquet will, in turn, be 55 cyanized and then pass into the cooling section 1', where its liquid content will congeal. In so doing the briquets in said section will adhere together to form a rather rigid structure, which will be sustained by the rotating table and will in turn sustain 60 the remainder of the charge in the retort.

The laterally self-sustaining character of this briquet structure permits the nitrogen flowing through the casing 4, to gain free access to the interior of the column, from all sides of the latter and thence up to the reaction zone. 70

The rotation of the table causes the teeth and other abrading parts of the eccentrically pivoted star or cutter to bite off pieces from the bottom of the column, and these loose 75 fragments are gradually worked off of the table and fall through the hopper 24 into the cooling tank; there being no lateral supports around the lower end of the column to hinder this movement. Pulverization of 80 the briquet material should preferably be avoided to favor the subsequent recovery of the cyanogen compound by an extracting operation.

Nitrogen supplied from pipe 32, cools the 85 briquets in the cooling tank and thereafter lowers the temperature of those in the casing 4 and retort section 1'; the nitrogen being preheated thereby.

Meanwhile the charge in the retort is renewed so as to maintain said retort substantially full; and if the reaction gases be not collected as they emerge from the hopper 8, they will burn at this point. 90

It has been found most convenient and 95 practicable, however, to make no attempt to recover these gases; the hopper 8 being left open to permit of the free introduction of the charge.

The substantially cold briquets in the 100 lower end of the tank are withdrawn, from time to time or continuously, as desired, and especially in the latter mode of operation, is it desirable to provide some means, such as the valve 26 and its associated parts, to 105 prevent wastage of the nitrogen supplied to the retort; or, even worse, such an outflow of both cooled briquets and nitrogen from the receptacle 25, as might tend to create a backward flow of nitrogen not only 110 through the cooling tank, but even downwardly through the retort; since in such case free atmospheric oxygen would also flow down from the open upper end of said retort.

I may add, that I have found it advantageous to thus supply nitrogen to the bottom of the cooling receptacle, in order to more efficiently and economically cool the briquets while at the same time conserving 120 much of the heat of which they are deprived. 115

In conclusion, I desire to point out that my invention not only contemplates the novel apparatus above described; but also 125 the method of fixing nitrogen made possible by this or an equivalent construction. This method is, in certain of its aspects, especially concerned with the turning to advantage in several ways, of what otherwise 130

would tend to give rise to considerable trouble in the nitrogen fixing operation. I refer here more particularly to the chilling and congealing of the cyanid formed, following its removal from the heat zone; which congelation, as above noted, has been favored under controlled conditions and utilized to aid in the subsequent preparation of the cyanized material for the extracting operation.

Having thus described my invention, what I claim is:

1. In apparatus for treating free nitrogen to effect the fixation thereof, the combination of a furnace having therein a cyanizing retort, with means to effect a gradual movement of cyanized material out of said retort at a temperature below that at which the cyanid formed congeals, said means including a toothed device for breaking off fragments of said cyanized material and power-driven means for actuating said device.
2. In apparatus for treating free nitrogen to effect the fixation thereof, the combination of a furnace having therein a cyanizing retort, with means to effect a gradual movement of cyanized material out of said retort in the form of a substantially rigid column, said means including a movably mounted device for picking to fragments the said material at the base of the column and power-driven means for actuating said device.
3. In apparatus for treating free nitrogen to effect the fixation thereof, the combination of a furnace having therein a cyanizing retort, with means to effect a gradual movement of cyanized material away from the heat zone of said retort in the form of a substantially rigid porous column, said means including a rotarily mounted device for picking to pieces and progressively removing said material at the base of the column, and means to supply nitrogen directly to portions of said rigid column as said portions become accessible to said nitrogen by their movement away from the walls of said retort.
4. In apparatus for treating free nitrogen to effect the fixation thereof, the combination of a furnace having therein a cyanizing retort, with means to effect a gradual movement of cyanized material out of said retort at a temperature below that at which the cyanid formed congeals, said means including a toothed device for breaking off fragments of said cyanized material, a rotary table upon which said device is loosely pivoted and means to drive said table rotarily, the axis of rotation of the table being eccentric to that of said device.
5. In apparatus for treating free nitrogen to effect the fixation thereof, the combination of a furnace having therein a cyanizing re-

tort, with means to effect a gradual movement of cyanized material out of said retort at a temperature below that at which the cyanid formed congeals, said means including a toothed device for breaking off fragments of said cyanized material, a rotary table upon which said device is loosely pivoted and means to drive said table rotarily.

6. In apparatus for treating free nitrogen to effect the fixation thereof, the combination of a furnace having therein a cyanizing retort, with means to effect a gradual movement of cyanized material out of said retort at a temperature below that at which the cyanid formed congeals, said means including a rotary table to support said material, means to drive said table and means to cut away fragments from the bulk of said material as the material of which said fragments are composed approaches said table.

7. In apparatus for treating free nitrogen to effect the fixation thereof, the combination of a furnace having therein a cyanizing retort, with means to effect a gradual movement of cyanized material out of said retort at a temperature below that at which the cyanid formed congeals, said means including a rotary table to support said material, means to drive said table and a toothed star pivoted upon said table eccentrically with respect to the table axis, to enable parts of said star to cut away fragments from the bulk of said material as the material of which said fragments are composed approaches said table.

8. In apparatus for treating free nitrogen to effect the fixation thereof, the combination of a cyanizing retort, means co-acting with gravity to cause a general but substantially continuous movement of cyanized material out of said retort, means to reduce said material to fragments, a flat cooling tank to receive said fragments, and means to supply free nitrogen to said tank and retort.

9. In apparatus for treating nitrogenous materials, the combination of a retort in which free nitrogen is first combined with other materials to form a fluid nitrogenous compound, and in which retort, further, said compound is subsequently solidified, with means to co-act with gravity to effect a gradual extrusion of solidified material from said retort while breaking said material into fragments, means to receive and cool said fragments, means to supply free and relatively cool nitrogen to the mass of said fragments in said cooling means, to aid in lowering the temperature of said mass while preheating said nitrogen, and provisions to control the movement of cooled fragments out of said cooling means.

10. In apparatus for treating nitrogenous

- materials, the combination of a retort in which free nitrogen is first combined with other materials to form a fluid nitrogenous compound and in which retort, further, said compound is subsequently solidified, with a rotary table to support the charge in said retort, means, carried by said table, for breaking up solidified material extruded from said retort, and means to rotate said table step by step.
11. In apparatus for treating nitrogenous materials, the combination of a retort in which free nitrogen is first combined with other materials to form a fluid nitrogenous compound and in which retort, further, said compound is subsequently solidified, with a rotary table to support the charge in said retort, means, carried by said table, for breaking up solidified material extruded from said retort, a worm and wheel drive for said table, and step by step acting means for operating said drive.
12. The combination of a vertical retort, with means for heating the same, a casing connected to the lower end of said retort, mechanism in said casing, to co-act with gravity to feed the charge from said retort, means to drive said mechanism, a cooling repository to receive the material removed from said retort, means to control the movement of cooled material out of said repository, and means to supply a gas to be treated in said retort to said repository at a point near the bottom thereof.
13. In apparatus for treating free nitrogen to effect the fixation thereof, the combination of a furnace having therein a cyanizing retort, with means to effect a gradual movement of cyanized material out of said retort at a temperature below that at which the cyanid formed congeals, said means including a rotary table to support said material, means to drive said table and a picking device pivoted upon said table eccentrically with respect to the table axis, to enable parts of said device to pry away fragments from the bulk of said material as the material of which said fragments are composed approaches said table.
14. In combination, a furnace having
- therein a retort in which a constituent of the material emerging from said retort tends to act adhesively upon cooling, with means to effect a gradual movement of said material out of said retort at a temperature at which said material is adhered together by said constituent thereof, said means including a rotarily mounted support for said material, means to drive said support rotarily, and a device mounted upon said support eccentrically with respect to the rotary axis of the support, for picking off fragments from the bulk of said material as the material of which said fragments are composed approaches said support.
15. In combination, a furnace having therein a retort in which a constituent of the material emerging from said retort tends to act adhesively upon cooling, with means to effect a gradual movement of said material out of said retort at a temperature at which said material is adhered together by said constituent thereof, said means including rotarily mounted supporting means for said material, means to drive said supporting means rotarily and means for prying off fragments from the bulk of said material as the material of which said fragments are composed approaches said supporting means.
16. In combination, a furnace having therein a retort in which a constituent of the material emerging from said retort tends to act adhesively upon cooling, with means to effect a gradual movement of said material out of said retort at a temperature at which said material is adhered together by said constituent thereof, said means including a rotarily mounted support for said material, and a device pivotally mounted upon said support for prying off fragments from the bulk of said material as the material of which said fragments are composed approaches said support.
